COMBINATION TOWEL DISPENSER AND RECEPTACLE THEREFOR

Ralph W. Biggar, 360 Aurora Crescent,
Burlington, Ontario, Canada

Filed May 28, 1969, Ser. No. 17,401

Term of patent 14 years

Int. Cl. D9—99

U.S. Cl. D52—2

FIG. 1 is a front perspective view of a combination towel dispenser and receptacle therefor showing my new design;

FIG. 2 is a front perspective view of a second modified embodiment of the design shown in FIG. 1;

FIG. 3 is a front perspective view of a third modified embodiment of the design illustrated in FIG. 1; and

FIG. 4 is a front elevational view of all the embodiments the only difference residing in the side rear configurations of the various modified forms.

I claim:

The ornamental design for a combination towel dispenser and receptacle therefor, as shown and described.
